CLAIM

The ornamental design for a football-shaped telescope, as shown and described.

DESCRIPTION

FIG. 1 is a left side elevational view of a football-shaped telescope showing our new design, it being understood that the right side is a mirror image thereof;

FIG. 2 is a top plan view thereof, it being understood that the bottom is a mirror image thereof;

FIG. 3 is a front end view thereof;

FIG. 4 is a rear view thereof;

FIG. 5 is a rear perspective view with the end cover removed; and,

FIG. 6 is a rear perspective view shown in open condition with the end cover removed.
